HOSPITAL GARMENT

Louise Severance, New York, N. Y.

Substituted for abandoned application Serial No. 300,769, October 23, 1939. This application July 21, 1943, Serial No. 495,630

1 Claim. (Cl. 2—114)

This application is a substitute for my application Serial No. 300,769, which was filed on October 23, 1939.

This invention relates to hospital garments and is herein illustrated as embodied in a garment especially suited for the patient in convalescence or for such patients required to spend a great deal of time in bed, as is required of patients in sanitariums or those permanently disabled, such as many are in government hospitals and public institutions.

The model herein illustrated has an attached collar which folds over, giving the appearance of a tailored soft shirt collar, permitting the quick adjustment of a neck-tie. The absence of any opening in the front of the coat and the form which permits the use of a neck-tie allows the patient to don a dressing gown quickly and without the effort of "changing" from one garment to another and at the same time giving the appearance of being completely dressed.

A closed front with the additional luxury of three large pockets, one with stitched space for pencil or pen; adequately covering the body and at the same time allowing easy accessibility to the body for any required treatment, assures the feeling of refinement from undue exposure and gives the appearance of normality when the dressing gown is worn over this type of coat. These garments meet the psychological need in affecting the appearance of the patient, made possible in design and construction as well as adequately meeting the need of the doctor and nurse in the medical care of the patient. This is a problem never before been solved in the required clothing for hospitalization.

In the form illustrated the sleeves include overlapping front and rear breadths which are left unstitched so that the sleeves are readily opened throughout their length, but fall together naturally.

The collar may be partly divided in front so that it naturally falls over and cooperates with an ordinary neck-tie to give a dressy appearance.

Other features and advantages will hereinafter appear.

In the accompanying drawing,

Fig. 1 is a front view of the garment;

Fig. 2 is a rear view; and

Fig. 3 shows the garment laid out flat.

The garment illustrated includes a front breadth 10 which extends from the armhole 11 to armhole 12. Under the armholes the front breadth 10 is stitched by a vertical seam to a right back breadth 13 and a left back breadth 14, and each back breadth 13, 14 is also stitched to the front breadth 10 by a shoulder seam 15.

Each sleeve 16 is made by stitching back breadth 17 to the edge of the armhole 12 so that the front edge of the back breadth 17 lies about an inch in front of the shoulder seam 15, and

also stitching the front breadth 18 to the edge of the armhole 11. But the front breadth 18 overlies the back breadth 17 at the armhole 11 because its top edge 19 lies about an inch behind the shoulder seam 15.

The sleeve 16 is shown as ending in a cuff 20 to which the front sleeve breadth 18 and the back sleeve breadth 17 are both stitched so as to leave the ends 21 and 22 of the cuff open. 10 This permits the garment to be put on to a patient without slipping the sleeves over the patient's arms, because all that is needed is to pass the armhole over the patient's hand and up the arm. The cuff is then closed by passing the long end 22 through a slot 23 in the cuff end 21 a little behind the edge 19 where it joins the cuff.

The end 22 is buttoned by a buttonhole 24 to a button 25 and the end 21 is buttoned to a button 26.

To cause the sleeve 16 to fall properly over the arm, each sleeve front breadth is shown as including a three-quarter inch lengthwise tuck 27 at the shoulder seam 15, the tuck extending down to the cuff 20 at the slot 23.

In the form shown the garment includes a collar 28, nearly divided at 29 in front and adapted to fold over a neck-tie, and open at the neck but adapted to be closed there by a button 30, on the broad seam 31 which forms the edge of the garment, and over which is buttoned the buttonhole 32.

The garment is shown as provided with side pockets 33 and with a left hand breast pocket 34 which includes a stitched compartment 35 to hold a pen or pencil.

On one of the side seams 36 is shown a loop 37 for holding a belt 38 adapted to be tied around the waist.

The single collar button and the belt adequately hold the garment on the collar presenting a handsome appearance, the sleeves adequately covering the wearer's arms, yet by releasing the button and the cuffs and the belt, the garment 40 may be slipped off the patient with almost no exertion by the patient.

Having thus described one embodiment of the invention, what is claimed is:

A hospital garment having a closed front and open back and forming a body with armholes, a sleeve at each armhole and including a front breadth and a back breadth leaving an opening between them, a shoulder seam running to each armhole, the back breadths springing from the armholes in front of the shoulder seams, the front breadths overlying part of the back breadths and springing at their rear edges from the rear of the armholes behind the top shoulder seams, and continuations of the sleeve openings 50 forming open cuffs for the sleeves.

LOUISE SEVERANCE.
